UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A CAM FOR SASH-FASTENERS.

SPECIFICATION forming part of Design No. 33,618, dated November 27, 1900.

Application filed August 3, 1900. Serial No. 25,841. Term of patent 14 years.

To all whom it may concern:

Be it known that I, WARREN H. TAYLOR, of Stamford, Fairfield county, State of Connecticut, have invented and produced a new and original Design for a Cam for a Sash-Fastener, of which the following is a full, clear, and exact description, reference being had to the accompanying drawings, forming a part thereof.

In the accompanying drawings, Figure 1 is a top view, and Figs. 2 and 3 are views of opposite sides, of the fastener.

The leading feature of my design consists of a cam having a flange around its cam edge disposed at right angles thereto and inclined from a point near one end to the respective ends thereof, a circular disk or protuberance on the cam having a twisted lateral projec-

tion thereon and a circular button or enlargement on the disk or protuberance.

3 represents a cam having a flange 4 around its cam edge extending up at right angles thereto and inclined downward from a point 5 near one end to the respective ends of the cam edge. A circular disk 6 is located on the cam 3 and provided with a twisted lateral projection 7, and a circular button 8 is located on top of the disk 6.

What I claim is—

The design for a cam for a sash-fastener herein shown and described.

WARREN H. TAYLOR.
